IRONING MACHINE

Gustav B. Keil, St. Joseph, Mich., assignor to
 Nineteen Hundred Corporation, Binghamton,
 N. Y., a corporation of New York

Application April 2, 1936, Serial No. 72,249

1 Claim. (Cl. 45—68)

This invention relates to domestic ironing machines and more particularly to an improved cover construction for such machines.

A feature of the invention is the provision of a cover that either may be tilted or otherwise shifted from a position concealing the ironing devices to one exposing the same or may be readily and completely removed from the machine to provide greater access to the ironing devices. 5 It has been a particular object to devise a construction of this character that is simple, inexpensive, and easy to handle.

Other features and advantages of the invention will appear from the detailed description of an 15 illustrative form of the same which will now be given in conjunction with the accompanying drawings, in which:

Fig. 1 is an end view of the upper portion of a 20 ironing machine showing the cover in an elevated position above the machine to indicate the manner of applying and removing the cover.

Fig. 2 is a vertical, sectional view through the 25 upper portion of the machine showing the cover in full lines in its concealing position and in dotted lines in its tilted or exposing position.

Fig. 3 is an enlarged, elevational view along the line 3—3 of Figure 1, showing a cover hinge in detail.

Fig. 4 is an enlarged section along the line 30 4—4 of Figure 2, showing a detail of the corner construction of the cover, and

Fig. 5 is a vertical section along the line 5—5 of Figure 4 showing a detail.

Referring now to the drawings, there is shown 35 in Figures 1 and 2 the top table portion 10 of a supporting structure of any convenient form. In general the ironer may be of the type illustrated in the Haney Design Patent No. 95,037 granted April 2, 1935. At one end of the table there may 40 be provided a housing 11 which serves as the support for the ironing elements and encloses the operating gearing and control devices therefor. The ironing elements may include a shoe 12 supported from an arm 13 by means of a pair of 45 links 14, the upper of which has connected therewith a handle 15 by which the links 14 may be rocked to carry the shoe away from a roller 16. It will be understood that in addition to this manual means for shifting the shoe, there will 50 be provided power-driven means within the housing 11 for rocking the arm 13, in a manner not shown but well known in the art.

Heretofore it has been the common practice to leave the ironing elements and the supporting 55 structure, described above, exposed at all times.

In accordance with the present invention, however, a cover is provided to normally conceal these parts. This cover, as best shown in Fig. 2, is preferably formed in three sections, including a front section 17, a similar back section 18, and 5 a central section 19. The front section has an outwardly projecting flange 20 along its inner edge extending around three sides of a rectangle while the rear section 18 has a similar flange 21. Central section 19 is provided with cooperating flanges 22, which may be secured in any convenient way, as by welding, to the flanges 20 and 21. The net result of this construction is to provide a box-like structure having an open bottom and having a central, raised band formed 10 by the section 19 extending around the ends and the top of the cover which will then present an appearance substantially as shown in my Design Patent No. 98,072 granted January 7, 1936. Preferably the three sections of the cover are formed 20 of sheet metal, although any other suitable material might be used in lieu thereof. The bottom edges of the sections 17 and 18 are preferably folded back upon themselves, as indicated at 23, to eliminate a sharp, lower edge. At the front of 25 section 18 the folded bottom portion may be of slightly greater extent and its upper end may be bent into a V-shape, as indicated at 24. This will afford additional stiffness and strength to the relatively long section extending substantially from one end to the other of the cover. The lower edges of section 19 are bent inwardly 30 in a horizontal direction to the plane of the ends of sections 17 and 18 and may, if desired, be doubled back upon themselves to avoid the formation of a sharp, free edge.

At the corners of the front section 17 provision is made for retaining a pad element 26 formed of rubber, felt or any other suitable material which may engage the top 10 without scratching 40 the same and will prevent rattling of the cover as the machine is moved about. Any convenient means may be provided for retaining the pad 26 in place, such as a bracket 25 having its upper portion welded or otherwise secured to the inner 45 face of section 17 and having an inwardly and downwardly bent portion providing a pocket to receive the pad 26. The pad, as shown, extends downwardly below the lower edge of the cover to a slight extent and is adapted to cooperate 50 with an angular portion 27 formed at the edge of the top 10. It will be understood that this construction is duplicated at the two front corners.

For supporting the back of the cover there is 55 preferably attached to the section 18 a plurality

of hook elements 28 bent to provide a downwardly opening hook 29. One of these elements is secured, as by welding or the like, to the back face of section 18 adjacent each corner. If desired one or more additional hook elements of the same type may be provided intermediate the ends of the back section or, if preferred, a single long hook extending substantially from end to end of the cover might be employed. In vertical alignment with the hooks 29 there is attached to the frame of the machine, as by welding to the top portion 10, a bracket 30 extending some distance above the top 10. It will be understood that a bracket of this sort is provided for each of the hooks 29. Each bracket is provided with a pair of upstanding portions 31 curled around a pin 32. This pin is held firmly by the curled ends 31 and is prevented from axial movement by side portions 33 bent rearwardly from the brackets 30. These side portions lend rigidity to the bracket and also extend partly across the ends of the pin 32 to retain the latter. When the cover is in place on the machine, the hooks 29 will engage their respective pins 32 and thereby provide a firm support for the back of the cover.

When it is desired to expose the ironing elements and use the machine, the cover may simply be tilted backwardly about the pins 32 as a pivot until the cover assumes the dotted-line position shown in Fig. 2. In order to retain the cover in this position, suitable limiting means is preferably provided at each end. For this purpose a plate 34 is preferably secured to the inner surfaces of the ends of the cover, as by welding to the ends of the sections 17 and 18. These plates bridge across the channel formed by the section 19. A pivot pin 35, preferably located near the lower back corner of each of the plates 34, carries a downwardly extending link 36. This link passes through a slot 37 formed in the top 10 adjacent the end of the latter and is provided with a notch 38 adapted to engage the rear edge of the slot when the cover is tilted into the dotted-line position (Fig. 2). It will be seen that in this way the movement of the cover is automatically limited as it is tilted backwardly about the pivot pins 32.

At times the space available when the machine is in use may be insufficient to permit the cover to be tilted in the manner explained or it may be that appropriate access to the ironing elements requires more complete removal of the cover. For this purpose the cover may be simply raised into the position shown in Fig. 1, care being taken to

rock the links 36 forwardly a slight extent to prevent engagement of the notch 38 with the rear edge of the slot 37. There is nothing then to prevent the complete removal of the cover, which may be set aside as desired. Rocking of the links 36 for this purpose may be effected in various ways, as by holding each of them with a finger as the cover is raised or by simply tilting the cover forwardly, as it is raised, to a sufficient extent to prevent engagement of notch 38 with the end of slot 37.

Accordingly it will be seen that the present invention provides a construction in which the cover may, under normal circumstances, be tilted backwardly around a fixed pivot and held in a position at 90 degrees to its original position while at the same time complete detachment of the cover from the machine may be readily effected by a simple bodily movement of the cover. In shifting the cover from the closed to the dotted-line position of Figure 2 it may, if desired, be lifted slightly before rocking it backwardly. This would cause temporary disengagement of the hooks 29 from pins 32 and would normally be done only in case the cover were of such size and form that it could not be rocked backwardly without first lifting it.

While an illustrative form of the invention has been described in considerable detail, it will be understood that numerous changes may be made in the construction and arrangement of the various parts without departing from the principles and scope of the invention. The terms and expressions employed herein are to be understood as terms of description and not of limitation.

What I claim is:

In combination, a frame, a cover, means for supporting said cover on said frame, said means providing a fixed pivot hinge comprising a fixed pivot on one of said members, a readily disengageable open hook on the other of said members for detachable and pivotal connection with said pivot, said frame having a slot, and a link pivotally attached to said cover arranged to cooperate with said frame at said slot to limit the pivotal movement of said cover to substantially 90°, said link being detachable from said frame to permit complete detachment of the cover when raised bodily to disengage said open hook, the open hook being arranged vertically so that said link will prevent bodily horizontal movement of the cover when the cover is at the limit of its opening movement.

GUSTAV B. KEIL.
